UNITED STATES PATENT OFFICE.

HENRY CURLAND, OF CHICAGO, ILLINOIS, ASSIGNEE TO HIMSELF AND CHARLES H. KELLERMANN, OF CHICAGO, ILLINOIS, A COPARTNERSHIP.

APPARATUS FOR COOLING SOAP AND THE LIKE.

1,244,297.

Specification of Letters Patent. Patented Oct. 28, 1917.

Application filed August 9, 1916. Serial No. 113,950.

To all whom it may concern:

Be it known that I, HENRY CURLAND, a subject of the German Empire, residing at Chicago, in the county of Cook and State of Illinois, have invented certain new and useful Improvements in Apparatus for Cooling Soap and the like, of which the following is a specification.

The present invention relates to a mechanism for cooling soap, stearin, wax, paraffin, gelatin, cocoa butter, and like substances, which, in process of manufacture, are heated to a liquid state and then cooled to harden.

In the manufacture of soap, as well as certain other substances, it is common to heat the ingredients in a caldron or kettle, where they are reduced to liquid state. After a sufficient heat treatment, the fluid is poured out into suitable receptacles where it may cool and harden. In this art it has been found difficult to expedite the cooling process by natural or artificial means. When cooled by natural processes, a great length of time is consumed,—perhaps as much as one, two or three weeks, and during all this period much material and capital is necessarily tied up, and the completion of the product to its final state is greatly delayed.

Recognizing the disadvantages attendant upon a slow cooling of such fluids, I have devised an improved apparatus for speeding the cooling operation. In general, this apparatus seeks to expedite the cooling of the fluid by artificial means, so as to bring the fluid into a hard and cooled state within a period of a few hours; to subject the fluid under treatment to cooling influences which are uniform at every point; and to accomplish the above ends by means which are simple, certain and inexpensive in operation. With these and other objects in view, I have provided a heating vessel into which the fluid is received from the caldrons or kettles, and a cooling apparatus into which the liquid is periodically introduced from the heating vessel at such times as new quantities of fluid are to be treated to the cooling action.

An embodiment of my invention, designed particularly for the cooling of soap, is shown in the several figures of the accompanying drawings, in which:—

Figure 1 is a rear side elevation of the

apparatus in its entirety, showing the heating vessel connected operatively with the cooling apparatus, portions of both parts being cut away to exhibit the interior construction;

Fig. 2 is a fragmentary side elevation showing a modified form of compression means for the cooling and soap units;

Fig. 3 is an enlarged section through one of the water cooling units, taken on line 3—3 of Fig. 4;

Fig. 4 is a transverse section through several cooling units and soap units, showing their relative arrangement in the cooling apparatus;

Fig. 5 is an enlarged section of one of the soap units, taken on line 5—5 of Fig. 4, exhibiting the unit in partially tilted position preparatory to removal of the solidified soap mass;

Fig. 6 is a detail in perspective of the chain or link connections between the cooling and soap units;

Fig. 7 is a fragmentary detail, showing in elevation the roller and chain construction for supporting the cooling and soap units;

Fig. 8 is a horizontal section through one of the cooling units, taken on line 8—8 of Fig. 3;

Fig. 9 is a detail in cross-section of the valve which shuts off the flow of liquid soap into the cooling apparatus;

Fig. 10 is a detail of one of the vents used in each of the soap units;

Fig. 11 is a cross-section through the valve stem used in the vent shown in Fig. 10;

Fig. 12 is a detail, front view, of the roller and link construction showing its connection with the front end of one of the soap units;

Fig. 13 is a detail, side view, of the parts shown in Fig. 12;

Fig. 14 is a detail, front view, of the roller and link construction, showing its connection with the rear end of one of the soap units; and

Fig. 15 is a detail, side view, of the parts shown in Fig. 14.

The general arrangement of the component parts of my invention are shown comprehensively in Fig. 1, wherein is exhibited a vessel 16, preferably of cylindrical form having a valved inlet 17 through which hot

soap fluid is received from the caldrons or kettles. It may be found desirable to employ within the vessel an agitator such as that illustrated, consisting of a rotatable shaft 18, having blades or paddles 19 extending radially therefrom, the shaft at its upper and lower ends being journaled as at 20 and 21, respectively, in the axial line of the vessel. At its upper end the shaft 18 projects through the vessel, a beveled gear 22 being secured to the shaft end, a second gear 23, carried on a horizontal stub-shaft 24, being arranged to engage therewith. When power is applied to rotate the shaft 24, the shaft 18 and blades within the vessel are likewise revolved. Interiorly, I have also arranged other blades or paddles 25 upon the walls of the vessel to increase the agitation of the fluid when the shaft 18 is revolved. The vessel may also be provided with an inlet 26 for the admission of air under pressure to assist in forcing the soap fluid into the cooling apparatus which will presently be described.

25. The vessel 16 is elevated and supported by means of standards 27. From the bottom side of the vessel an eduction pipe 28 leads off to the cooling apparatus, the delivery end of this pipe 28 being supported in a bearing or frame 29 of substantial construction, which immediately adjoins the cooling apparatus. The eduction pipe is surrounded throughout its entire length by a water jacket 30. At its delivery end this pipe is provided with a shut-off valve 31, which includes a plunger 32 and a hand wheel 33, by which the plunger is operated. The plunger 32 normally occupies a position at the extreme end of the eduction pipe 28, as best shown in Fig. 9. The valve plunger is equipped with a cone head 34 which is arranged to enter an opening formed in the proximate cooling unit, the body of the plunger abutting against the unit to form a closure against the passage of soap fluid. The cone head may also be used to force out of the proximate water unit presently to be described, any solidified soap which may remain there after the cooling operation, so as to clear a passage for the introduction of a fresh charge of fluid soap.

Surrounding the vessel 16 is a water jacket 35 communicating directly with the eduction pipe jacket 30, and also through the medium of a circulation line 36. The water within the jacket 35 is heated by steam introduced through a supply pipe 37 equipped with a controlling valve 38, and an injector 39, which latter is connected to the eduction pipe jacket by means of a pipe 40. An overflow pipe 41 is also provided, being connected with the water jacket 35 near its upper end. In case it should be found desirable to clean out the parts in which the soap fluid is contained, a blow-out steam pipe 42 may be used for this purpose, a valve 43 being provided for controlling the passage of steam through this pipe.

The heating vessel, which has already been described, is intended to receive and preserve at proper temperature a charge of liquid soap prior to passing into the cooling apparatus. This apparatus which is situated immediately adjacent the delivery end of the eduction pipe includes a number of 75 water cooling units 44, alternating with a number of fluid soap units 45. As will be seen from Figs. 1 and 9, the delivery end of the eduction pipe 28 terminates squarely at the far side of the supporting frame 29. To 80 this same side of the frame the first cooling unit, designated as 46, is likewise secured by bolts or any other suitable means. Between the frame 29 and a second supporting frame 47 I have arranged at unequal elevations 85 channel iron beams, the lower beam 48 extending along the front side, and the upper beam 49 along the rear side, of the cooling apparatus. It is between these beams that the water and soap units are alternately arranged in the manner shown in Fig. 1.

The construction of the water cooling units 44 will now be described. Each of these units may conveniently be formed of metal, and comprises front and rear walls 95 50 and 51, respectively, (see Fig. 3), side walls 52 extending between the front and rear walls of the unit, and top and bottom walls 53 and 54, respectively. The units 44 are relatively thin in a transverse direction, 100 so that the side walls are spaced but a slight distance apart. Extending transversely between the side walls of each unit in a vertical direction are a number of partitions 55 terminating short of the top and bottom 105 walls so as to leave upper and lower passages extending from the front to the rear of the unit. Extending from the rear to the front wall of the cooling unit within the lower passage is a distribution pipe 56 having upwardly facing discharge openings 57 which may be spaced closer together, according to their proximity to the front wall of the unit. One end of this distribution pipe projects through the rear end of the 110 unit where it is connected to a flexible pipe 58, which communicates with a supply pipe 59 for the cooling water. Through the parts just described cool water is admitted into the interior of each water unit, 120 where it is distributed from one end to the other by the pipe 56 and discharged at a substantially uniform rate at every point throughout the length of the unit. The water thus discharged is caused to flow upwardly between the partitions 55 to the upper end of the unit. An outlet 60 is here provided for taking off the water which has traveled from the bottom to the upper part of the unit, and for discharging it into a 125 65

trough 61 which runs the length of the apparatus upon its rear side. Near the bottom of the unit I have arranged a duct 62 in the form of a sleeve extending between the side walls of the unit, the purpose of which will be presently explained. Each of the water units is constructed substantially alike, so that the description of but one will be understood to apply to all.

10 In the water units just described it will be noted that the circulation of cooling water proceeds first vertically between the partitions and then horizontally across the upper portion of the chamber. In this manner the flow is controlled in certain definite directions so as to insure an even and uniform circulation of water throughout the chamber. The interchange of heat units is further facilitated by reason of the partitions which extend between the side walls of the chamber. Besides affording a greatly increased surface area for the cooling water to act upon, they strengthen the construction of the units and prevent crushing when 25 the units are subjected to pressure in the manner to be hereafter explained.

Exteriorly each water unit is provided on its rear end near its top with a bracket 63 providing a bearing for a shaft 64, upon 30 which a grooved roller or wheel 65 is mounted. This roller is arranged to travel upon a guide or rail 66 running lengthwise upon the upper surface of the channel iron beam 49. The front wall of the water unit is 35 likewise formed with a bracket 67 similar to the bracket 63, which also provides a bearing for a shaft 68 on which a grooved roller or wheel 69 is mounted. This wheel is likewise arranged to travel upon a guide 40 or rail 70 arranged upon the upper surface of the lower channel iron beam 48. In the construction shown, it is manifest that the water cooling units are each so mounted as to be capable of longitudinal movement between 45 the channel iron beams without interrupting the constant circulation of cooling water.

Between each pair of water units I have arranged a soap unit 45 (see Figs. 4 and 5), 50 this alternate arrangement of cooling and soap units rendering possible a rapid interchange of heat units, such as to speedily cool and harden the soap fluid. The soap units I prefer to construct of wood in the form 55 of an open frame with front and rear walls 71 and 72 respectively, and top and bottom walls 73 and 74 respectively. These soap units have no sides whatever, but in use are completely closed in between the adjacent water units so that a tight chamber 60 is provided within each frame for the reception of fluid soap. The ducts 62 extending transversely through each of the water units aline with each other so as to provide 65 an uninterrupted passage through

which the fluid soap may flow from one end of the apparatus to the other, when the shut-off valve 31 is opened for that purpose. In this manner the fluid soap may pass into each of the soap units to completely fill the 70 same, and if necessary air under pressure may be introduced into the vessel 16 to force the fluid soap to flow to its intended destination.

Escape of air from each of the soap units 75 as the soap is introduced therein is provided for in a vent 75, consisting of a sleeve 76 within which a stem 77 may move longitudinally, a head 78 being carried on the end of the stem to seat against the sleeve 80 to form a closure. The vent may be locked in closed position by means of an arm 79 loosely pivoted to the upper end of the stem, a spring 80 exerting tension upon the stem to hold the head against the sleeve when 85 the arm 79 is turned to vertical position. The vents 75 serve both to allow the escape of air during filling of the soap units, and to indicate a complete filling of each unit when the soap fluid commences to flow 90 through its vent, or when the arm 79 reaches its highest position, caused by the pressure of the rising soap fluid upon the head 78. The operators may then close and lock the vent in the manner described to prevent 95 further escape of soap fluid.

Each of the soap units is exteriorly provided upon its rear wall with a bracket 81 having a concave grooved portion therein, and upon its front side with a similar concave grooved bracket 82, the latter bracket being equipped with a shoe 83 extending downwardly into immediate proximity with a guide or rail 84 located on the upper surface of the channel iron beam 48 at its outer 100 edge. Engaged by each of the concave grooved brackets 81 and 82 is a collar or flange 85 carried by a link 86 having one end in the form of a slotted tongue 87 and the other end in the form of a slotted yoke 105 88. (See Fig. 6.) The yoke end of each of these links is arranged to embrace the tongue end of the adjoining link so as to form a complete chain. Two such chains are employed, one at the front side and the 110 other at the rear side of the apparatus. The front chain makes use of the shafts 68, and the rear chain makes use of the shafts 64, as pins for connecting the links together. On account of the slotted construction of 115 the openings in each end of the links, considerable play therebetween is provided for. As has been previously shown, rollers or wheels 65 and 69 are provided to carry the weight of the water and soap units. The 120 links which are connected to each of these units serve merely to prevent them from becoming spaced apart more than a fixed distance.

Referring again to Fig. 1, the water unit 125

situated farthest from the delivery point of the eduction pipe I have designated as 89. Abutting against the outer side of this unit is a block 90 having a head 91 and arranged 5 to move on rollers or wheels 92. This block is intended to remain always in vertical position so that it may bear squarely and evenly against the unit 89. In interior construction this unit is similar to the other 10 water units 44 already described, with the exception that it is not provided with any duct or sleeve 62 for the passage of liquid therethrough. Because of this fact, the unit 15 89 will act to close up at the end of the apparatus the passage formed by these ducts 62 so that the liquid soap will be retained properly within the chambers provided for that purpose.

During the cooling process the water and 20 soap units are compressed together with considerable force, and for this purpose I have arranged a compression device consisting of a cylinder 93 within which a piston 94 may move to advance a plunger 95 which 25 is connected with the block 90. For the purpose of operating the piston mechanism described, hydraulic pressure or other suitable means may be employed. In Fig. 2 I have shown a modified and simplified form of 30 compression means in which a hand wheel 96 is attached to a screw shaft 97, the shaft being threaded through the frame 47, so that it may be advanced when rotated. Obviously, such a manually operated means, or 35 any other appropriate device, may be used for the purpose of applying pressure to force the water and soap units into close relation.

After the fluid soap has been subjected for 40 a sufficient time to the cooling action of the water circulating throughout the water units, the soap mass will be reduced in temperature and become solidified so that it may be removed from the several soap units. To 45 remove the solidified masses of soap from the frames, I contemplate an operation somewhat as follows: The pressure applied to the water and soap units is first released, so that the several units may separate 50 slightly from each other, the amount of separation being limited by the play of the links in the chains which engage each of these units. The soap units are then tilted one at a time, through ninety degrees or 55 more, a unit in partially tilted position being exhibited in the dotted lines in Fig. 5. This tilting movement is toward the front of the machine, and causes the bracket 81 on the rear side of the frame to disengage 60 from the collar or flange 85 on the chain link. The guide 84 serves as a pivot for this tilting movement, the shoe 83 engaging with the guide for this purpose. When the soap unit has been tilted sufficiently, the 65 soap mass may be ejected from the frame

and removed for further treatment as required. The solidified portions of soap remaining in the ducts 62 and vents 75 may also be removed to clear these passages for the reception of additional charges of 70 liquid soap. After the frames have each been relieved of the soap mass, they are then returned to their normal position, where the brackets 81 again engage with the collars or flanges 85 for the purpose of preserving the 75 several units in proper spaced relation. It will be noted that the several water and soap units are supported on the rollers and connecting chains at points above their centers of gravity, so that these units tend 80 always to remain in vertical position. The arrangement of the two channel iron beams at unequal elevations, the front beam being the lower, enables the soap units to be tilted without interference with the rear beam. 85

The advantages derivable from the cooling apparatus of my invention are many. The mechanism not only reduces the temperature of the fluid soap in a much shorter time than has been previously done, but the 90 space required for the mechanism is very considerably less. Furthermore, by introducing the fluid soap into the soap units under pressure, I have eliminated the presence of air holes. The soap units, furthermore, are entirely inclosed, so that the mass remains in darkness during its cooling operation. This circumstance, as well as the fact that the soap may be quickly and intensively cooled, results in a harder and 95 lighter product than is usually obtained. In fact, it is possible in the present apparatus to produce a harder soap with the same ingredients, or the same soap with a greater percentage of cheaper raw materials, than in the case of soap ordinarily 100 manufactured. 105

It will be noted also that the cooling influences act uniformly upon the soap mass at every point in the apparatus which I have devised. This tends to insure uniformity throughout the soap mass. The percentage of waste, which in the manufacture of soap oftentimes amounts to as much as twenty-five per cent., is reduced to 110 practically nothing in the present apparatus. The losses which occur through drying are negligible, as the soap is cooled 115 within closed chambers where it is subjected to almost no drying action. 120

I claim:

1. A cooling apparatus of the character described comprising a plurality of cooling chambers, a plurality of units adapted to contain the material to be cooled, arranged 125 adjacent to and in alternation with said chambers, said units being pivotally mounted, whereby a tilting action thereof is facilitated.

2. A cooling apparatus of the character 130

- described comprising a plurality of cooling chambers, arranged in alternation to a plurality of units adapted to contain the material to be cooled, each of said units being 5 supported at one side above and at the other side below the center of gravity thereof, whereby a tilting action is facilitated.
3. A cooling apparatus of the class described comprising a plurality of cooling 10 chambers mounted on rollers at front and rear, and a plurality of pivoted container units arranged in parallelism and alternation with said chambers, said units being also supported by said rollers.
- 15 4. A cooling apparatus of the class described comprising a frame the front and rear top surfaces of which constitute tracks, a plurality of cooling chambers carried by said frame, said chambers being provided 20 with rollers at front and rear and engaging said tracks, a plurality of container units arranged adjacent to and in parallelism and alternation with said chambers and lost motion 25 connections between said rollers at front and rear, said units being detachably mounted upon said connections.
5. A cooling apparatus of the class described comprising a frame having a high rear surface and a relatively low front surface constituting tracks, a plurality of cooling 30 chambers carried by said frame, said chambers being provided with rollers at front and rear and engaging said tracks, a plurality of container units arranged adjacent to and in parallelism and alternation with said chambers and lost motion 35 connections between said rollers at front and rear, said units being detachably mounted upon said connections.
- 40 6. A cooling apparatus of the class described comprising a plurality of cooling chambers, a plurality of container units ar-
- ranged adjacent to and in parallelism and alternation with said chambers, means for filling said container units with the material to be cooled, ports permitting the egress of air from said units as they are being filled and visual signals for positively indicating the filled condition of the units, substantially as described. 45
7. A cooling apparatus of the class described comprising a frame carrying a plurality of cooling chambers, a plurality of container units arranged adjacent to and in alternation therewith, rollers mounted at the rear of each of said chambers, above the center of gravity, and rollers mounted at the front of each of said chambers, below the center of gravity, tracks provided on the frame 50 and adapted for said rollers, a lost motion device connecting the shaft of each roller to the adjacent roller shaft, each of said units being provided upon its front and rear face with a bracket resting upon said lost 55 motion device, substantially as described.
8. A cooling apparatus of the character described comprising a plurality of aligned cooling chambers, a plurality of tiltably mounted units adapted to contain a material 60 to be cooled, said units being arranged in alignment and alternation with said chambers, means for feeding a cooling agent to said chambers, means for feeding the material to said units, means whereby said chambers and units may be moved into close contact, and means for facilitating separation 65 of said units and chambers to a specified extent, whereby said units are freed for the tilting thereof, substantially as described. 70
